UNITED STATES PATENT OFFICE

165,928

CHRISTMAS TREE HOLDER

Edward Parucki, Lackawanna, and Edmund S.
Cebulski, Buffalo, N. Y.

Application September 7, 1951, Serial No. 16,556

Term of patent 3½ years

(Cl. D35—3)

To all whom it may concern:

Be it known that we, Edward Parucki and Edmund S. Cebulski, citizens of the United States of America, residing respectively at Lackawanna and Buffalo, county of Erie and State of New York, have invented a new, original, and ornamental Design for Christmas Tree Holder, of which the following is a specification, reference being had to the accompanying drawing, forming a part hereof, in which

Fig. 1 is a top plan view of a Christmas tree holder showing our new design.

Fig. 2 is a front elevation thereof.

We claim:

The ornamental design for a Christmas tree holder, as shown.

EDWARD PARUCKI.
EDMUND S. CEBULSKI.
